UNITED STATES PATENT OFFICE.

ERNEST S. BARKER, OF BROOKLINE, MASSACHUSETTS, ASSIGNOR TO UNITED DRUG COMPANY, OF BOSTON, MASSACHUSETTS, A CORPORATION OF MASSACHUSETTS.

DISPENSER FOR LIQUIDS.

1,216,199.

Specification of Letters Patent. Patented Feb. 13, 1917.

Application filed September 21, 1911. Serial No. 650,582.

To all whom it may concern:

Be it known that I, ERNEST S. BARKER, of Brookline, in the county of Norfolk and State of Massachusetts, a citizen of the 5 United States, have invented certain new and useful Improvements in Dispensers for Liquids, of which the following is a specification.

Certain goods are dispensed at soda fountains which should be agitated from time to 10 time in order to keep them in proper condition. It has been the custom with such liquids to place them in a bottle or container, and invert the bottle so that the liquid is 15 drawn from the inverted nozzle as occasion may require, the air which rushes in as the liquid flows out serving to bring about the required agitation.

For various reasons this construction is 20 undesirable and attempts have been made to provide a substitute therefor wherein the liquid will be agitated by mechanical means. This also is undesirable because with any 25 mechanical means there are more parts to be kept clean and kept in operative condition.

My invention comprises a dispenser wherein the container may be in the form of a bottle or otherwise as seems desirable, which container has a drawoff or faucet located in its bottom and an inlet in the shape 30 of a tube passing down through the stopper or other device which closes its top, to the bottom below the drawoff, this tube being open at both ends so that as the liquid is 35 drawn off from the container the air to supply its place will flow down through the tube and be delivered to the bottom of the container from which it will bubble up to the space in the container above the liquid.

40 The bottom of this tube may be either plain or it may be so shaped as to dispense the air in different directions.

My invention will be understood from the drawings in which devices embodying my 45 invention are illustrated.

Figure 1 is a vertical section of a container presumably of glass; and

Fig. 2 shows a modification of the tube shown in Fig. 1.

50 A is the container having an opening at the top closed by a plug B. Through the center of this plug extends downwardly a

tube C open at the top to the atmosphere and open at the bottom either in the manner shown in Fig. 1 or as shown in Fig. 2 where- 55 in the end of the tube is shown to be closed as at c, and perforations c¹ are provided ex- tending in various directions so that the air will be delivered on various sides of the bottom of the tube. 60

D is a faucet of ordinary construction, the neck d of which passes through a suitable opening (which may be reinforced as shown) in the side of the container, the neck d being threaded and the faucet being held 65 in place by a nut d¹ which binds against a washer d², another washer d³ being shown lying between the exterior of the container and an enlargement d⁴ on the faucet. The faucet D is located in the side of the con- 70 tainer A slightly above the bottom of the container and also at a point slightly above the lower end of the tube C. This is neces- sary to prevent the drawing off of sediment or thickenings present in such liquids as 75 orangeade or lemonade.

It will be seen that upon opening the faucet so as to draw liquid from the container air will rush in to supply the place of such liquid and as the air is lighter than the 80 liquid it will bubble up through the liquid thus causing it to be thoroughly mixed.

As there is usually quite frequent call for liquids of this character, for example, orangeade and the like, the constant bub- 85 bling up of the air with each draft from the container will cause the liquid to be con- stantly agitated so that the ingredients will be thereby constantly mixed.

Other embodiments of this invention will 90 occur to those skilled in the art.

What I claim as my invention is:

A dispenser comprising a stationary tank 95 of greater depth than horizontal diameter provided with a draw-off located in the lower part of its side and having an intake communicating with the interior of the tank at a point above the bottom thereof so as to be above sediment accumulated upon said bottom, said tank having a filling opening in its top, a closure for said filling opening, and an air tube passing through said closure having an open upper end and a lower end 100 communicating with the interior of said

tank adjacent the center of the bottom thereof and below the level of the intake of said draw-off, whereby air discharged from the bottom of said tube serves to stir up sediment on said bottom, thence passes upwardly on all sides of said tube to agitate all parts of the contents of said tank, and in passing

said intake serves to clear the same of sediment.

ERNEST S. BARKER.
